UNITED STATES PATENT OFFICE.

ENOCH OHNSTRAND, OF MOHAWK, NEW YORK, ASSIGNOR TO LIBRARY BUREAU, OF CAMBRIDGE, MASSACHUSETTS, A CORPORATION OF NEW JERSEY.

FIRE-RESISTANT CABINET.

Application filed January 28, 1922. Serial No. 532,444.

To all whom it may concern:

Be it known that I, ENOCH OHNSTRAND, a citizen of the United States of America, and resident of Mohawk, in the county of 5 Herkimer and State of New York, have invented new and useful Improvements in Fire-Resistant Cabinets, of which the following is a specification.

This invention relates to improvements in 10 fire resistant cabinets such as vaults, safes, filing cases, etc., designed for the protection of documents and other valuables from fire.

When cabinets of this character are subjected to intense heat, as in a fire, the slight 15 amount of moisture always present in the heat insulating material between the outer and inner metallic casings is changed to steam. When this steam contacts the hot outer casing an inflammable and explosive 20 gas is produced. If this gas is present in any considerable quantity, it is liable to bulge the casings which confine it. In any case the presence of this gas in a confined state endangers the contents of the cabinet, 25 since a disruption of the protective casings by pressure or explosion of the gas entails the destruction of the contents of the cabinet by fire, or damage to them by smoke and water.

30 Objects of the invention are to prevent bulging and disruption of the protective casings of fire resistant cabinets, to provide a ready means of escape for gases generated within said casings to preserve the usual 35 appearance of such cabinets by normally concealing necessary openings therein, and in general to improve devices of this character.

The invention comprises partially filling 40 the space between the outer and inner casings of heat-resisting cabinets and venting the unfilled space. The unfilled space is preferably adjacent the outer casing and is in the form of recesses or channels in the 45 heat insulating material or in the casing. The venting ducts lead from the channels out through the outer casing. The unsightly openings in the outer casing are concealed in any suitable manner as by inserting in the ends thereof plugs of readily fusible material such as wax, or of some 50 soft metal as lead, or a fusible alloy.

In order to illustrate the invention one

concrete embodiment thereof is shown in the accompanying drawings, in which — 55

Fig. 1 is a perspective view;

Fig. 2 is a horizontal sectional view on the line 2—2 of Fig. 1;

Fig. 3 is a perspective view, diagrammatic in form, taken from the opposite side of the 60 safe from that shown in Fig. 1; and

Fig. 4 is a sectional view on the line 4—4 of Fig. 3.

The invention is illustrated as embodied in a safe A having an angle iron frame B, 65 swinging doors C pivoted to the frame at D, lock dial E and bolt operating handles F. The safe has inner and outer metallic walls or casings G and H respectively, the space between the walls being occupied by 70 an inner insulating air space I and a thick mass of heat insulating material J.

In view of the fact that gases are generated within the walls of a safe by the heating of the insulating material J adjacent 75 the outer casing H and that these gases tend to gather between the outer casing and the insulating material, the invention contemplates the provision of air spaces for the collection of such gases. This air space 80 might be in the form of a gap or space between the casing and the heat insulating material, but such casing sometimes bulges inwardly when expanded by heat; hence the air spaces are preferably made in the form 85 of grooves or depressions K in the heat insulating material adjacent the outer casing. While the grooves forming these air spaces 90 may be as numerous as desired and disposed in any direction, the arrangement here shown comprises a continuous groove or depression, the parts of which are substantially parallel with the edges of the safe. To permit the gases which collect in the air 95 spaces K to escape, vents L of suitable size and of suitable number in the form of grooves or ducts in the insulating material extend to the outer casing of the safe, preferably at the top where they connect with the holes m extending through the outer casing and the frame thereover. To prevent an unsightly appearance, these openings are closed by plugs n of wax or some other 100 readily fusible material.

Air spaces are likewise formed in the 105 doors C in a similar manner but the vents

comprise holes O through the face of the door as indicated in Fig. 1. These holes preferably connect directly with the upper horizontal portion of air space. These 5 openings, being more conspicuous than the openings in the door of the safe, are closed with plugs P of lead or other readily fusible metallic alloy in order to take the fine finish of the front of the safe without chipping, 10 denting or cracking.

In case a safe provided with air spaces and vents as herein described is subject to great heat, plugs n and P will fuse, providing a ready and easy means of escape for 15 any gases which may form between the safe casings. Since these air spaces or ducts lie within the body of the heat insulating material, they cannot be rendered inoperative by inward buckling of the outer casing of 20 the safe.

For the purpose of venting the space filled or partly filled by the heat insulating material it is immaterial whether the vent passages or channels are made in the insulating material itself or in one or both of the 25 casings of heat conducting material, such as metal, which define the space. Thus the receptacle may be considered as having walls as composed of alternate layers of heat 30 conducting and heat insulating material with channels in one or more of the layers to vent the interior of the walls. The channels, however, are preferably formed in the insulating material, since to make them in 35 the metal casings would tend to weaken the resistance of the receptacle to shocks and blows due to falls and explosions.

I claim:

1. A fire-resistant cabinet having inner 40 and outer casings, heat insulating material between said casings of a kind which generates gas when heated, and means for venting the portion of the cabinet between said casings to the exterior of the cabinet in order 45 to relieve the pressure due to the formation of gas from said material, whereby deformation of the cabinet by interior gas pressure is avoided in case of fire.

2. A fire-resistant cabinet having inner 50 and outer casings, heat insulating material between said casings leaving a space unfilled adjacent one of said casings, said insulating material being of a kind which generates gas when heated, and means for vent- 55 ing said unfilled space to the exterior of the

cabinet to relieve the pressure due to the formation of gas from said material thereby to avoid deformation of the cabinet by interior gas pressure in case of fire.

3. A fire-resistant cabinet comprising adjacent layers of heat conducting and heat insulating materials, said heat insulating materials being of a kind which generates gas when heated, channels formed in one of said layers wherein the gas may gather, and 60 means for venting said channels to the exterior of the cabinet, whereby deformation of the cabinet by interior gas pressure is avoided in case of fire.

4. A fire-resistant cabinet having inner 70 and outer casings, heat insulating material between said casings, leaving a space unfilled adjacent one of said casings, said insulating material being of a kind which generates gas when heated, a vent extending 75 from said unfilled space through said outer casing, and a fusible plug in said vent, whereby deformation of the cabinet by interior gas pressure is avoided in case of fire.

5. A fire-resistant cabinet having inner 80 and outer casings, heat insulating material between said casings, said material being of a kind adapted to generate gas when heated, a channel in said material adjacent one of said casings, and a vent extending from 85 said channel through said outer casing, whereby deformation of the cabinet by interior gas pressure is avoided in case of fire.

6. A fire-resistant cabinet having inner 90 and outer casings, heat insulating material between said casings, said material being of a kind adapted to generate gas when heated, a channel in said material, a vent extending from said channel through said outer casing, and a fusible metal plug in said vent, 95 whereby deformation of the cabinet by interior gas pressure is avoided in case of fire.

7. A fire-resistant cabinet comprising adjacent layers of heat conducting and heat insulating material, said heat insulating material being of a kind adapted to generate 100 gas when heated, channels formed in certain of said layers, vents for said channels, and fusible means normally closing said vents, whereby deformation of the cabinet by interior gas pressure is avoided in case of fire.

Signed by me at Mohawk, N. Y., this 24th day of January, 1922.

ENOCH OHNSTRAND.
